UNITED STATES PATENT OFFICE.

FREDERICK J. EDGARS, OF BROOKLYN, NEW YORK, ASSIGNOR TO THE
E. B. ESTES & SONS, OF AUBURN AND FARMINGTON, MAINE, AND
NEW YORK, N. Y.

DESIGN FOR A WOODEN BOX.

SPECIFICATION forming part of Design No. 25,642, dated June 16, 1896.

Application filed November 13, 1895. Serial No. 568,870. Term of patent 14 years.

To all whom it may concern:

Be it known that I, FREDERICK JAMES EDGARS, a citizen of the United States, residing at Brooklyn, in the county of Kings and State 5 of New York, have invented and produced a new and original Design for a Wooden Box, of which the following is a specification, reference being had to the accompanying drawings, in which—

10 Figure 1 is an elevation; Fig. 2, a plan, and Fig. 3 a vertical section.

The general configuration of the box is round, with the upper part of less diameter than the lower part, and the leading features 15 of my design consist in the compound curved surfaces between the two cylindrical portions, a rib with a compound curved surface at the upper part of the smaller cylindrical portion,

and a groove and rib at the bottom of the box.

The top *a* is flat with tapering sides *b*. The body is cylindrical at *c*, and with a portion contracted in diameter at *d*, with a projecting rounded rib *e* at the upper edge, and the intermediate compound curves at *h*, and the bottom of the body is grooved at *o* and rounded, as a bead, at *i*.

I claim—

The design for a wooden box, substantially as herein shown and described.

Signed by me this 9th day of November, 3c
A. D. 1895.

FREDERICK J. EDGARS.
